[57] CLAIM

The ornamental design for a segmented helicopter float,
as shown.

DESCRIPTION

FIG. 1 is a top front perspective view of the segmented
helicopter float.

FIG. 2 is a bottom rear perspective view thereof.

FIG. 3 is a side elevation view thereof.

FIG. 4 is a top plan view thereof.

FIG. 5 is a front end view thereof.

FIG. 6 is a rear end view thereof.

The broken line showing of a portion of a helicopter in
FIGS. 1 and 2 is for illustrative purposes only.
